UNITED STATES PATENT OFFICE.

EDWARD W. JENKINS, OF NORRISTOWN, PENNSYLVANIA.

GRAIN-BINDER.

SPECIFICATION forming part of Letters Patent No. 280,481, dated July 3, 1883.

Application filed February 7, 1883. (No model.)

To all whom it may concern:

Be it known that I, EDWARD W. JENKINS, of Norristown, Montgomery county, and State of Pennsylvania, have invented an Improvement in Grain-Binders, of which the following is a specification.

My invention has reference to grain-binders; and it consists in certain improvements fully set forth in the following specification, 10 and shown in the accompanying drawings, which form part thereof.

The object of my invention is to dispense with the overhanging arm and heavy framework now in general use on harvesters and 15 binders, and using in lieu thereof a direct arm or bracket made stationary to one side of the binder-frame, and pivoting thereto an oscillating binder-arm which is adapted to convey the cord to the knotter, and in its operation to 20 thread and unthread, so as not to carry the cord up and cut off the delivery, but, instead, to drop the cord and allow a free passage for the bound bundle to be discharged out across the feed opening or inlet by way of the binder-arm, the said inlet being placed between 25 the knotter and the discharge-opening. The sheaf is discharged sidewise, and not endwise. This binder is more rigid and direct-acting than those with the overhanging arm, which 30 adds heft and complication to the machine.

The binder is provided with a table, or a receptacle to receive the incoming grain through a feed opening or inlet, so arranged with reference to the cord-actuating devices as to 35 have the cord extended across the mouth of the inlet to the knotter, whereby the grain, by being fed through the feed-opening, is delivered into a band, one end held by the knotter on one side of the inlet, and the other end passing 40 around the grain through the table on the opposite side of said inlet. When the grain is fed into the receptacle, the binder-arm, as it closes in and compresses the sheaf or gavel, catches up the cord band and conveys the 45 spool end of the cord to the knotter, where the band is secured around the sheaf and cut, leaving a new end held fast in the holder near the knotter, with the cord extending across the inlet to the spool, as before.

50 Figure 1 is a side elevation of my improved grain-binder in the act of having a gavel fed thereto. Fig. 2 is a similar view, showing the

binder-arm closed upon the bundle. Fig. 3 is a front elevation of same, and Fig. 4 is a modified form of cord-carrying device.

A is a stationary arm or bracket of the binder, having a guide-finger, A', and supporting the oscillating binder-arm B, pivoted upon a stud, G. The binder-arm is worked by a crank, C, upon the rotating shaft C, working in a journal-box upon the upper end of the bracket A, which shaft C may be driven by means of a connecting-rod or pitman, D, connecting the crank with the binder-arm B, one end of the pitman being connected to the said binder-arm at D', and the opposite end to the crank-pin C'.

Fig. 2 represents the binder-arm closed in upon the gavel and compressing it by a chain or strap, F, fastened to one arm of bell-crank F', pivoted at f' to the bracket A of the binder, and having its movement limited by a lug, f'', against which its free leg rests. Said chain passes through the binder-arm over roller g, and is fastened to a take-up lever, H, pivoted 70 on the binder-arm at h, to take up and tighten the chain around the bundle by means of a spring, I, upon a rod, I', said rod being hinged to the binder-arm at i, extending through the 75 said spring and a hole, K, in the take-up lever. 80

The table or receptacle W is framed to the binder, and provided with a feed opening or inlet, L, of any desired construction, through which the grain is fed, said inlet being placed between the knotter O' and discharge-opening 85 R. The table is provided with a guide-casting, M, having a groove or channel, m, for the the end of the binder-arm to pass through in its travel to and from the knotter O'.

The cord O is threaded through the casting 90 M, as shown, and then carried to the knotter, where it is held, it being drawn across the feed-opening L in the path of the incoming grain. The binder-arm is provided with an opening or slot, P, on the end to catch the 95 cord O as the said arm passes through the channel m in the casting M, the cord being caught up in the opening and guided over a roller, p. As the binder-arm closes into the knotter it compresses the sheaf through the 100 agency of the chain F, and conveys the cord O to the knotter O', in the meantime drawing the cord tight around the bundle. When the binder-arm opens again, the cord drops out of

the opening in the end of the arm and is left in its original condition, and is not drawn out and up with the binder-arm, thereby leaving a discharge-opening, R, between the table and 5 guard-finger A, through which to discharge the bundle by way of the binder-arm, and which is done in this case by the ejecting-fingers S, secured to the rotating crank-shaft C, which comes around about the time the binder-arm is raised to allow the bundle to follow and be discharged across the feed-opening L and through the discharge-opening R.

If desired, when two discharging-fingers S are used, one may be secured to the shaft C 15 and the other to the crank-pin C², this latter finger being bent to bring it in line with the first finger, as shown.

In operation the grain is fed in through the feed-opening to the receptacle, taking up cord 20 around it until a sufficient length of cord has been pulled out, when the shaft C is rotated, and the binder is set in motion thereby. When starting, the crank-shaft rotates with the ejecting-fingers thereon in direction of the arrow, 25 which movement closes the binder-arm, compressing the gavel and catching up the cord and conveying it to the knotter, as in Fig. 2, and while in this position the crank is pulling on the pitman and passing the dead-center, 30 giving to the binder-arm a rest while the knot is made, and as the crank-shaft is driven on around, the knot is finished and the binder-arm rises above the guide-finger A', clear of 35 the bundle, which follows and is discharged through the opening R by the ejecting-fingers.

In place of making the binder-arm thread and unthread itself every time, I may use a separate needle, B', which may be pushed forward by the binder-arm B, and drawn back 40 by a band, B², and spring B³, or other equivalent device, as shown in Fig. 4. In this case the needle need never unthread itself, and is very similar in construction to the point of the binder-arm, if the same were cut off.

45 Having now described my invention, what I claim as new, and desire to secure by Letters Patent, is—

1. In a grain-binder, the stationary bracket and binding-table having a feed-opening, in 50 combination with mechanism so arranged as to discharge the bundle out across the feed opening or inlet of the binding-table, substantially as and for the purpose specified.

2. In a grain-binder, an oscillating binder- 55 arm that in its downward motion threads itself, and conveys the binding-cord to the knotter, and which, when returning, unthreads and leaves the cord below the bound bundle,

in combination with means to oscillate said binder-arm, a binding-table having a feed-opening across which said binder-arm passes, a cord-knotter, and means to eject the bound bundle out across said feed-opening, substantially as set forth.

3. In a grain-binder, an oscillating arm to 60 compress the grain and convey the cord to the knotter, in combination with a binding-table provided with a feed-passage and ejecting-fingers that discharge the bundle, causing it to follow the binder-arm in its movement from 70 the knotter and pass out across the feed-passage, substantially as and for the purpose specified.

4. In a grain-binder, the bracket A, supporting an oscillating arm to compress the 75 grain and convey the cord to the knotter, in combination with said knotter, located below the binding-table, a discharge-passage, and a feed opening or inlet for the grain through the binding-table of the binder, located between the knotter and the discharge-opening, 80 substantially as and for the purpose specified.

5. In a grain-binder, an oscillating binder-arm, in combination with a rotating crank-shaft provided with a crank, and ejecting-fingers secured thereon to discharge the bundle, 85 a connecting-rod to connect said crank to said binder-arm, a binding-table having a feed-opening through the same, and over which said ejecting-fingers force the bundle in discharging it, substantially as and for the purpose specified. 90

6. In a grain-binder, a stationary or rigid bracket, A, extending from the binding-table at or about in line with the binding-arm, in 95 combination with the pivoted binder-arm, a cord-knotter, a guide for the binding-cord, and a feed-passage for the grain, arranged between the said knotter and cord-guide, the said binder-arm being adapted to gather in the cord 100 around the bundle and feed the spool end to the knotter, substantially as and for the purpose specified.

7. The combination of bracket A, binding-table W, feed-aperture L, binder-arm B, shaft 105 C, crank 'C', connecting-rod D, knotter O', cord-guide M, means to compress the bundle, and means to discharge the same when bound, substantially as and for the purpose specified.

In testimony of which invention I have here- 110 unto set my hand.

EDWARD W. JENKINS.
